UNITED STATES PATENT OFFICE.

CHARLES BALDWIN, OF QUINCY, ILLINOIS.

PNEUMATIC MACHINE FOR PICKING COTTON.

SPECIFICATION forming part of Letters Patent No. 451,589, dated May 5, 1891.

Application filed July 12, 1890. Serial No. 358,583. (No model.)

To all whom it may concern:

Be it known that I, CHARLES BALDWIN, of Quincy, Adams county, Illinois, have invented a new and Improved Pneumatic Machine for Picking Cotton, of which the following is a full, clear, and exact description, reference being had to the accompanying drawings, forming a part hereof.

My invention relates to cotton-harvesters; and it consists in certain new and useful improvements in that class of the said machines which are adapted to pick cotton by means of a blast of air, and in the construction, arrangement, and combination of the parts of which it is composed, as will be hereinafter specified, and pointed out in the claims.

In the drawings, Figure 1 is a rear end view of a machine constructed in accordance with my invention. Fig. 2 is a vertical section on line *v v* of Fig. 3. Fig. 3 is a sectional plan view, the section being taken on line *x x* of Fig. 2. Fig. 4 is a detail view showing the air-nozzles located in one of the gathering-chambers, the section being taken on line *y y* of Fig. 1; and Fig. 5 is an elevation of same, taken on line *z z* of said Fig. 1.

1 indicates the axle of a suitable cart or vehicle, having supporting-wheels 2 and a suitable gear-wheel 3. Upon this axle I locate a number of gathering-chambers 4, (preferably two,) which may be mounted in a vertical line or which may be inclined so that their upper ends converge toward each other, as shown. Above the line *x x* (see Fig. 2) these chambers 4 unite with a centrally-located chamber 8^a, having the downwardly-projecting deflecting-wing 17 in its center, between the chambers 4, the top of the chamber 8^a on each side of the wing 17, having apertures 15 therein, covered with wire-netting 15^a to permit the escape of the air and to prevent the escape of the picked cotton. The chamber 8^a is centrally situated over the receiver 8, into which the material is discharged and from which it can be removed from time to time by opening its bottom 5, which is loosely attached thereto and held in place by suitable fastening devices, or the said receiving-chamber may be otherwise constructed to accomplish this dumping or discharging operation.

The lower ends of the chambers 4 are per-

fectly open and are cut away at their forward and rear sides, as at 6, forming thereon a forked or bifurcated end, which passes 55 astride the rows of plants during operation of the machine, as will be explained farther on, the forks on the forward sides of the chambers 4 being of greater length than those upon the rear, which is caused by the cut-away portion of the forward side being greater 60 than that cut away in the rear.

A suitable fan or other pneumatic current-inducer 7 is located on the machine, preferably in rear of chamber 8, (the receiving-chamber,) and having a shaft 9 suitably connected with gear-wheel 3, for the purpose of driving said fan at a rate of speed which will induce a forcible current of air to be driven out of the said fan into the distributing-pipes 7^c 10, which extend on either side and communicate with the interior of the gathering-chambers 4, and have branches and nozzles 12 therein so arranged as to discharge currents of air forcibly upward therein when the machine is in operation.

The blast-pipes 10 are pivoted at 13 to the fan-casing, so that their outer ends may be adjusted up or down to suit small or larger plants, the construction of their manner of 8^c attachment to the said chambers being as follows: The rear of each of the said chambers is vertically slotted at 10^a opposite the cut-away portion on the front face thereof, and through the said slot project nozzles 12, 85 secured to the said blast-pipes, that portion of the slots not occupied by the said nozzles being closed by a sliding arc-shaped shield 10^b carried thereon. It will thus be seen that the nozzles, whose forward upper ends are 90 beveled in order that they will throw an upward blast, can be moved vertically. The chamber 8^a has rounded outer corners 16 above the upper ends of the chambers, which will direct the flying cotton inwardly against 95 the centrally-located plate 17, whence it will be deposited, as indicated by the arrows, within said receiving-chamber.

18 is a bar or rod extended across the lower portion of the chambers 4 transversely to the passage-ways formed therein by the bifurcations, against which the plants strike in passage of the machine over them, the function of which is to hold the plants in a forwardly

bent position a little longer than they otherwise would be held, so as to the more perfectly subject them to the action of the air-blasts.

- 5 In some cases I may change the wheels 2 for larger or smaller ones, according to the height of the cotton-plants at the time of operation, instead of adjusting the blast-pipes for that purpose, as before stated herein.
- 10 The operation is as follows: The machine is driven in the field so that the bifurcated or forked lower ends of the gathering-chambers "straddle" the rows of plants, and as the machine advances the iron 20 of the bifurcated ends of the chambers 4 will run upon the plants and cause them to bend forward, and then, as the machine continues its forward movement, the plants will spring into an upright position within said chambers and 25 finally will be engaged by the transverse bars 18 and held a short time during the forward movement, and the forcible blasts of air from nozzles 12 will engage the cotton-bolls and detach them from the plants and carry them upward and deposit them, as before stated, in the receiving-chamber.

Having thus described my invention, what I claim is—

1. In a cotton-picker, the combination, with 30 an upright chamber with notches in its open lower end at front and rear, of a transverse bar near the base of the said chamber, a nozzle entering the said chamber near its base, and a fan connected with the said nozzle, as described.
2. In a cotton-picker, the combination, with 35 an upright chamber having its forward and rear sides notched at the lower open end, the notch of its forward side being deeper than that of its rear side, of a forwardly-projecting nozzle entering the said chamber from the rear and opposite the notched forward por-

tion, and a fan connected with the said nozzle, as described.

3. In a cotton-picker, the combination, with 45 an upright chamber having its forward and rear sides notched at the lower open end, the notches of its forward side being deeper than that of its rear side, of a forwardly-projecting nozzle entering the said chamber from the rear 50 and opposite the notched forward portion, the said nozzle having a beveled face upon the upper side of its forward end, a fan connected with the said nozzle and transverse bar within the base of said chamber, as described.

4. The combination, with an upright chamber having notches in its open lower end at the front and rear, the notch of the front of the said chamber being greater than 60 that of the rear, the rear of the said chamber being slotted above the notch therein, of a nozzle contained within the said slot having a shield mounted thereon, a fan, and a pipe pivoted to the casing thereof and carrying 65 the said nozzle, as described.

5. The combination, with a central chamber having rounded corners, a deflecting-wing in the center thereof, and wire-netting on each side of the said wing, of a chamber connected 70 with the said central chamber on each side of the wing thereof, having notches in the open lower ends at front and rear, nozzles entering near the base of the said chambers, fans connected with the said nozzles, and a receiving-75 chamber located below the said central chamber and communicating with the bottom thereof, as described.

In testimony whereof I affix my signature in presence of two witnesses.

CHARLES BALDWIN.
